UNITED STATES PATENT OFFICE.

ALBERT A. GRIFFIN, OF DAVENPORT, IOWA.

CHIROPRACTIC TABLE.

1,337,312.

Specification of Letters Patent. Patented Apr. 20, 1920.

Application filed February 17, 1919. Serial No. 277,626.

To all whom it may concern:

Be it known that I, ALBERT A. GRIFFIN, a citizen of the United States, residing at Davenport, in the county of Scott and State 5 of Iowa, have invented certain new and useful Improvements in Chiropractic Tables; and I do hereby declare that the following is a full, clear, and exact description of the invention, which will enable others 10 skilled in the art to which it appertains to make and use the same.

This invention relates to improvements in balancing mechanism for chiropractic tables.

15 The invention has for its object to furnish a structure of a most simple form for supporting various weights to be carried by the table.

An object is to provide a structure where- 20 in the removal or insertion of a member, or members, will operate to change the relation between the part carrying the load, and the balancing means.

Another object is to improve on this class 25 of tables with regard to the relation the load-supporting means bears to the part carrying the load.

To the end that the invention may be understood, I have provided the accom- 30 panying drawings, in which,

Figure 1 is a plan of the base which sup- 35 ports the table, showing in section, a part of the table;

Fig. 2 is a vertical longitudinal section of 40 the same;

Fig. 3 is an end elevation of the base, showing parts in section;

Fig. 4 shows, in perspective, certain of 45 the working parts;

Fig. 5 is a longitudinal section of portions of the apparatus, showing one of the 50 positions of the parts;

Fig. 6 is a similar view showing parts in a different position;

Fig. 7 is a similar view of a modified 55 form; and,

Fig. 8 is an end elevation of the same.

1 indicates, as a whole, the base of the table which preferably comprises a bottom 50 portion, sides, and one end substantially as shown. 2 is the supporting member for the patient, the same being usually properly upholstered and otherwise provided with conveniences not necessary to describe. This 55 member is pivotally supported near one end at 3 upon a member 4 preferably compris-

ing an upstanding support at each side of the base as clearly shown in Fig. 1, all being common, however, to structures of this class.

5 indicates a series of long, flat flexible 60 members preferably of steel and tempered to render them spring-like. At one of their ends they are provided with supporting rollers 6 which, in practice, travel upon rails 7, but one of which is shown, Fig. 2. 8 is a 65 series of coil springs connected at one of their ends in a suitable manner with some part of the base. Their other ends are connected to angle-plates 9 attached to the described members 5. The latter at their ends 70 opposite those having the rollers include means, such as a rod 10, embraced by links 11, for example, pivotally attached to the short end of the member 2 in any suitable manner.

75 Thus far described, the device does not differ materially from the device shown in my pending application Serial No. 162,459, filed in the United States Patent Office on the 16th day of April, 1917. In that applica- 80 tion the coil springs 8 referred to herein were in separate groups and, depending upon the weight to be carried, one or more of the groups were manually connected to a fixed part of the base as required. In ad- 85 dition, the flat spring-like members of that application, denoted by 5 herein, were made to pass beneath a roller having a stationary position. As distinguished from that form, I use, in the present instance, certain of 90 said spiral springs or their equivalents, at- tached permanently between the base and the springs 5. Then, in order to provide for varying weights imposed upon the table, the roller is made adjustable substantially 95 in the direction of the point of support at 3, or laterally of the line of pull of the spiral spring, the purpose of which will become apparent. This adjustment may be pro- 100 vided for in a number of ways, two of which I have illustrated in the drawings. A study of the first six figures will make one of the methods entirely clear.

Upon the bottom of the base, which ex- 105 tends beyond its sides, are erected spaced standards 12, one of which is shown in per- 110 spective in Fig. 4. Their lower ends are suitably secured to angle-bars 13 clearly shown in Fig. 3 which embrace the lower corners of the base and suitably secured thereto.

14 is a member lying upon the tops of

the standards and connected at its ends to each and serving as a brace for the same. On the inner face of each standard is secured a pair of guide-ways 15 within which a plate 16 is vertically slideable. 17 is a roller having a shaft extension at each end, not shown, each having a bearing in one of said plates 16. At the top of each plate is a supporting shelf 18 lying beneath the member 14 described. Thus mounted, the roller 17 is free to have vertical movement with the plates 16.

In Fig. 2 the roller lies in its lowest position, the spring-like members 5, connected to the member 2 as described, lying beneath it. In this figure two blocks 19 will be observed which are inserted between the member 14 and the shelf 18. These blocks are, for convenience, about of a length equal to the distance between the standards 12 and their ends lie upon the two shelves 18 and they fill the space between the member 14 and the described shelves so that the roller will be prevented from rising from the position shown when pressure of the members 5 is applied thereto. When not in use the blocks are conveniently disposed of by placing them in suitable retainers such as straps 19 secured on the sides of the base.

In said Fig. 2 the member 2 is shown in its normal upright position for use, or in the position to receive a person in upright position in the usual way, the foot step usually employed not being shown. When said member is drawn down to the horizontal position the members 5, as shown in dotted lines, are drawn outward and up around the roller, drawing upon the springs 8. The pull of the latter, permanently connected as described, is sufficient, when the roller is in its lowermost position, shown to support the heaviest load that may be imposed.

In Fig. 5 but one of the blocks 19 is shown between the member 14 and the shelves 18. The roller, therefore, is permitted to move upwardly toward the pivot 3 or laterally of the line of pull to such an extent that the leverage of the table is rendered more effective so that with the same pull of the springs 8 a much lighter load can be balanced.

In Fig. 6 neither of the blocks is employed, the shelf portion 18 being permitted to move up to and against the member 14 in which position of the roller a still lesser load may be accommodated.

In Figs. 7 and 8 another form of the roller supporting mechanism is shown. 20 60 is a pair of arms pivoted at one of their ends upon suitable standards 21 of the base, one at each side of the latter, the other ends of the arms supporting between them the roller denoted by the character 22 beneath 65 which the flat members 5 lie, as before.

Two extreme positions of the arm and roller are shown and may be held in either position, or intermediate ones, by means of a rod 23 extending through holes 25 in the two standards 24. This, of course, is a mere modification and may or may not be used, while other ways of supporting the roller and providing for its movement laterally with respect to the line of pull of the springs 8 may be readily devised, since it is not my purpose to be confined to any particular structure for the purpose.

In the first six figures the members 18 indicate lodgments for the spacing blocks 19.

The change in position of the roller with respect to the pivot at 3 may be likened to the shifting of a weight, or equivalent power, with respect to the fulcrum of a lever. In this case the member 2 is the lever, and the springs 8 the weight, made variable in effectiveness through the change in its point of application by the adjustment of the roller.

The flat members or springs 5 act in their longitudinal movement to place tension on the springs 8, serving as the means to permit the table 2 to move on its fulcrum the while.

In some of the claims the springs 8 and the said flat members 5 will be referred to as an element since, as a matter of fact, they operate as one part or as a unit.

Having thus described my invention, I claim:

1. In a device of the character described, 100 the combination with an unbalanced lever fulcrumed between its ends, of a counter-balancing element operatively connected to the short arm of the lever including a laterally flexing non-stretching portion, a member mounted between the said portion and the fulcrum and receiving the said portion against it, said member being adjustable to fixed positions in a direction substantially perpendicularly to the line of pull of the 110 said counter-balancing element.

2. The combination with a table of the type set forth including an unbalanced lever, of a counter-balancing element operatively connected to the short arm thereof including a non-stretching laterally flexing portion lying beneath the fulcrum of the lever, and a member disposed between the lever and the said portion receiving the latter against it, said member being adjustable substantially perpendicularly to the line of pull of the element upon said lever. 115 120

3. The combination with a table of the type set forth including an unbalanced lever, a counter-balancing element including 125 at one end a non-stretching laterally flexing portion connected operatively to the short end of the lever, a member disposed between the lever and the portion, receiving the latter against it, and in use fixed in posi- 130

tion but adjustable substantially perpendicularly to the line of pull of the portion upon the lever.

4. In a device of the character described, 5 the combination with a table fulcrumed between its ends whereby to have a short arm and a long arm, and a counterbalancing element operatively connected to the short arm thereof constantly tending to raise the table 10 toward a vertical position, and including a non-extensible flexible portion, and a member disposed between the fulcrum and the flexible portion adapted to receive the latter against it and adjustable in a lateral direction 15 with respect to said portion, and means to secure the member in a desired position.

5. The combination with a device of the type set forth including a table fulcrumed between its ends in unstable equilibrium, 20 and an element operatively connected to its short arm and constantly tending to maintain the table in substantially an upright position on its fulcrum, and a member disposed between the fulcrum and the element 25 in the path of the latter adapted for adjustment in substantially the direction of said fulcrum, and means to secure the member in a desired adjustment.

6. The combination with a device of the 30 class described including a base, a table fulcrumed thereon having a long and a short arm, and an elastic element fixed at one end to the base and attached at its other end operatively to the said short arm, holding 35 the table normally upright on its fulcrum, of a member lying between the fulcrum and the element receiving the latter against it, and adjustable in the direction of said fulcrum.

40 7. The combination with a device of the class described including a support, a table fulcrumed thereon between its ends, and a balancing element connected at one end to the table and at its other end to the support 45 constantly tending to move the table upon its fulcrum, of a member disposed at

the apex of a triangle whose base is described by a line drawn between the points of attachment of the element, and beneath which the element lies, said member being 50 adjustable in the direction of said base, and means to secure the member in any one of several adjustments.

8. The combination with a device of the class described including a table fulcrumed 55 between its ends, and a counter-balancing element operatively attached to the table constantly exerting a pull tending to raise the table to an upright position, of a member having a position to receive the element 60 against it and adjustable laterally of the direction of applied force of the latter whereby to change the direction of that force with respect to the fulcrum of said table. 65

9. In a device of the character described, the combination with a table fulcrumed between its ends and having a short arm and a long arm, a counterbalancing element including a flat spring adapted to flex extending beneath the fulcrum of said table operatively connected to the short arm of the latter, and an adjustable member movable with respect to the spring in the direction of the flexing movement thereof. 75

10. In a device of the character described, the combination with a table fulcrumed between its ends and having a short arm and a long arm, a counterbalancing element including a flat spring adapted to flex extending beneath the fulcrum of said table operatively connected to the short arm of the latter, an adjustable member movable with respect to the spring in the direction of the flexing movement, and means to secure said 80 member in a desired position. 85

In testimony whereof I affix my signature in presence of two witnesses.

ALBERT A. GRIFFIN.
